(57) **CLAIM**

The ornamental design for a medical instrument for ophthalmic surgery, as shown and described.

DESCRIPTION

FIG. 1 is a perspective view of a medical instrument for ophthalmic surgery according to the present invention.

FIG. 2 is a front view of the medical instrument for ophthalmic surgery of FIG. 1.

FIG. 3 is a rear view of the medical instrument for ophthalmic surgery of FIG. 1.

FIG. 4 is a left side view of the medical instrument for ophthalmic surgery of FIG. 1.

FIG. 5 is a right side view of the medical instrument for ophthalmic surgery of FIG. 1.

FIG. 6 is a top view of the medical instrument for ophthalmic surgery of FIG. 1.

FIG. 7 is a bottom view of the medical instrument for ophthalmic surgery of FIG. 1.

FIG. 8 is a reference view showing an enlarged portion of the medical instrument for ophthalmic surgery of FIG. 1; and,

FIG. 9 is another reference view showing the medical instrument for ophthalmic surgery of FIG. 1 while in use. The broken lines in the drawings depict a portion and environment element of the medical instrument for ophthalmic surgery and form no part of the claimed design.

1 Claim, 9 Drawing Sheets
